CHAIN SAW

Richard W. Condon, Frankfort, Vernon L. Krabbe, Beecher, Henry R. Johannes, St. Anne, and Roscoe Combs, Kankakee, Ill., assignors to Roper Corporation, Kankakee, Ill.

Filed Nov. 16, 1970, Ser. No. 26,027

Term of patent 14 years

Int. Cl. D8—05

U.S. Cl. D8—65

FIG. 1 is a left hand side view of a chain saw embodying our new design.

FIG. 2 is a top view thereof.

FIG. 3 is a right hand side view thereof.

FIG. 4 is a front elevational view thereof, and

FIG. 5 is a rear elevational view thereof.

We claim:

The ornamental design for a chain saw, as shown and described.
